DESIGN FOR A TEXTILE FABRIC OR SIMILAR ARTICLE

Marion R. Hamre, Oceanside, N. Y., assignor to Charles Bloom Inc., New York, N. Y., a corporation of New York

Application March 24, 1948, Serial No. 145,313

Term of patent 7 years

(Cl. D92—1)

To all whom it may concern:

Be it known that I, Marion R. Hamre, a citizen of the United States, residing in the city of Oceanside, county of Nassau, and State of New York, have invented a new, original, and ornamental Design for a Textile Fabric or Similar Article, of which the following is a specification, reference being had to the accompanying drawing, forming a part thereof.

The figure of the drawing is a plan view of a textile fabric, showing my new design.

The horizontal dotted lines outline a design unit which is repeated over the fabric above and below in regular succession beyond said lines.

I claim:

The ornamental design for a textile fabric or similar article, as shown and described.

MARION R. HAMRE.
